UNITED STATES PATENT OFFICE.

ALOYSIUS MCHUGH, OF MCKEE'S ROCKS, PENNSYLVANIA.

RAILWAY-RAIL SPLICE.

SPECIFICATION forming part of Letters Patent No. 508,900, dated November 14, 1893.

Application filed March 11, 1893. Serial No. 465,635. (No model.)

To all whom it may concern:

Be it known that I, ALOYSIUS MCHUGH, a citizen of the United States, residing at McKee's Rocks, in the county of Allegheny and State of Pennsylvania, have invented certain new and useful Improvements in Railway-Rail Splices; and I do hereby declare the following to be a full, clear, and exact description of the invention, such as will enable others skilled in the art to which it pertains to make and use the same, reference being had to the accompanying drawings, which form a part of this specification.

My invention relates to an improved splice bar, for railway rails, and consists in certain details of construction, and combination of parts as will be fully described hereinafter.

In the accompanying drawings, Figure 1 is a sectional perspective view of my improved splice bar and railway rail, which is constructed in accordance with my invention. Fig. 2 is a perspective view of a portion of one of the splice bars. Fig. 3 is a perspective view of a portion of the other splice bar. Fig. 4 is a sectional plan view of the finished splice, said section taken on the line X—X of Fig. 1.

To put my invention into practice with ordinary railway rails 1, I provide a plate 2 adapted to fit against the inner side of the web of the rail, and pass over the inner flange, and beneath the rail to a point a short distance beyond the outer flange, and terminate in an inwardly sloping surface 5. Arranged opposite this plate 2 and at the other or outer side of the rail 1 is another plate 4 the lower edge of which is beveled to fit neatly against the inclined surface 5, and the upper edge beneath the tread of the rail, as will be seen by reference to Fig. 1 on the drawings. Each of these plates 2, and 4 is provided with circular depressions, formed on the inner surfaces, in which short tapering pins 6 are arranged, being first passed through openings formed

near each end of the rails 1. Each of these plates above described is provided with spike 45 openings 3—8, constructed and arranged in a manner that when the spikes are driven into the ties the two plates will draw tightly together.

In operation, the plate 2 is first placed in 50 position, each end of which is resting on separate ties, the pins 6 arranged in position, and the plate 4 slipped in position endwise. Spikes are now driven through the openings 3 at each end of the plate 2, and the splice or connection completed by driving spikes through the openings 8 of the plate 4 in a manner that the same will draw the said plate inward to wedge and support the tread of the rail 1, thereby forming a splice without the use of 55 bolts or nuts, and rendering the same solid, rigid, and substantial.

Having thus described my invention, what I claim, and desire to secure by Letters Patent, is—

In combination with the rails 1, the bar 2, constructed to fit neatly about the inner side of the web, the inner flange, and base of the rail, the inclined surface 5 projecting beyond the outer flange of the rails, the bar 4 one 70 edge resting on said inclined surface 5, and the other beneath the tread of the rails, the pins 6 passing through the rails into each of the said plates, and the openings 3, and 8 formed in the plates in a manner that when 75 spoked to the ties the same will draw the two plates together, all arranged and combined for service, substantially as and for the purpose described.

In testimony that I claim the foregoing I 80 hereunto affix my signature this 14th day of February, A. D. 1893.

ALOYSIUS MCHUGH. [L. S.]

In presence of—

MILES BRYAN,
M. E. HARRISON.
